PAGE 2

FIG. 2

FIG. 3

FIG. 4

FIG. 5

FIGURE 1 is a perspective view of a mixing box for an air conditioning system embodying my new design, as viewed from the front.

FIGURE 2 is a top plan view thereof.

FIGURE 3 is a front elevational view thereof.

FIGURE 4 is a side elevational view thereof with a portion of the rear shown in cross-section.

FIGURE 5 is a rear elevational view thereof with the screen member fragmentarily shown for convenience of illustration.

The dominant features of my design reside in the portions shown in full lines.

The cross lines indicating convention screening which is partially shown on the filters in FIGS. 1, 3 and 4, and

on the rear of the box in FIG. 5, is understood to cover the entire area shown.

I claim:

The ornamental design for a mixing box for an air conditioning system, substantially as shown and described.
